CONTAINER

Henry T. Scott, Toledo, Ohio, assignor to The American Paper Bottle Company, Toledo, Ohio, a corporation of Ohio

Application March 24, 1932, Serial No. 600,858

2 Claims. (Cl. 229—3.1)

This invention relates to containers and closures therefor.

This invention has utility when incorporated in paper, cardboard or fiberboard types of boxes or cartons, especially of the rectangular tubular form for setting up, together with features for the closure of the filled or charged container.

Referring to the drawings:

Fig. 1 is a view of the container exterior side of a scored blank incorporating an embodiment of the invention;

Fig. 2 is an end elevation of the closed container formed from the blank of Fig. 1;

Fig. 3 is side elevation of the container of Fig. 2;

Fig. 4 is a section, on an enlarged scale, on the line IV—IV, Fig. 3;

Fig. 5 is a section longitudinally thru the closure rib with the tuck-in flap out;

Fig. 6 is a fragmentary bottom plan of the container tube with but one minor bottom flap inwardly folded;

Fig. 7 is an enlarged section on the line VII—VII, Fig. 1;

Fig. 8 is an enlarged section of a carton closure corner folded with the score impressed line outward;

Fig. 9 is an enlarged section of a carton closure corner folded with the score impressed line inward; and

Fig. 10 is a view of the self spacing of the blanks in flat tubular form.

There is shown a scored blank. Preferably scoring 1 is not perforation, but such a marking as may be effected by a dull blade for depressing a groove 28 on one side and rib 29 opposite thereto to initiate a line for ready folding. This end is attained most effectively when the folding is with the groove 28 inward to be crowded a minimum. This leaves the rib 29 outside (Fig. 9) to be slightly stretched or taut with less danger of the plies of the material to open up (Fig. 8) to invite leakage problems, and is of especial importance at the closure corner.

Such scoring 1 defines tube sides 2, 3, 4, 5, (Fig. 1), with flap 6 from the latter to be assembled with the free edge of the side 2 in seaming the blank up into a tube. The opposing tube sides 2, 4, have minor inner bottom flaps 7, 8, foldable toward each other to approximate abutting relation at their free ends. Major bottom-forming flaps 9, 10, respectively from the opposing sides 3, 5, provide two-ply reinforcement for the sectional bottom 7, 8, in completing a three-ply end or closed bottom for the container, assembled by an adhesive 30, (Fig. 6). In practice glue is used.

When the finished article is to be used for liquids, this tube with but one open end may be coated with a leak-proofing substance 31, such as paraffin (Fig. 4).

Beyond the extent of the tube sides proper, closure sections may be collapsed to seal the container. The seam flap 6 (Fig. 1) has sections 11, 12, 13. The side 5 has sections 14, 15, 16. The side 3 has sections 17, 18. The sides 2, 4, each have an isosceles triangular section 19, a pair of right triangular sections 20, 21, and a pair of trapezoid sections 22, 23. With the flap 6 sealed by glue 32, in assembly with the side 2, there is tube continuity to include the triangular and trapezoid sections by the scoring assembly and the seam flap sections 11, 12, 13, adherent to the free edge region of the sections 19, 21, 23, from the side 2. Before the bottom is assembled the flat tubes may be supplied in a magazine for such operations of opening up, bottom forming, and coating. The ribs 29 so space (Fig. 10) the flat tubes in the magazine stack that ready separation is had for withdrawing separately and setting up. To open up the flat tube by edge pressure at the joint between the sides 2, 3, any tendency for cross locking or binding between the bottom sections is eliminated by cut out 33.

There is thus clearance for ready setting up of the flat tube into the open ended square duct. The three triangular sections 19, 20, 21, are a set, forming a parallelogram section of similarity to the sections 14, 17.

When there has been leak-proofing, it is desirable to relocate the scorings before final closing. To effect closing of the charged container, the sections 14, 17, are moved toward each other as the apices of the triangles 19 are folded inwardly. The trapezoid sections 22, 23, fold one on the other to meet medially of the section 15 for tuck-in section 16 to be thrust inside the section 18 toward the section 17. Then embracing section 18 may fold over to abut the outer side of the section 15. Stitching or wire staple 24 thru such assembly in the formed rib 25 may thus complete closing. Warming of the leak-proofing for softening or fusing may occur in such timing that when stitched or finally sealed there may be resealing on the folded lines.

Location of the seam flap in the triangle and minor bottom flap regions for fold-over assembly, effectively reinforces the seam, instead of the seam being a source of weakness in otherwise locating the seam.

In the collapsing of the closure, as the apex of the triangle 19 moves inward, the sides of the

right triangles 20, 21, connected respectively with the sections 14, 17, transmit a tilting tendency to the triangle 19 against full parallelism with the tube bottom. This tilting is slightly upward toward the central portion of the rib 25 while the sections 15 and 18 are spaced apart more than the thickness of the sections 22, 23. As the sections 22, 23, are flattened out by the more snug abutting assembly with the section 15, the greater extent abutting portion between the trapezoids 22, 23, holds up this two-ply intermediate portion to approximate straight line continuity of the free edge portion thereof as identical with the fold line between the sections 15, 16. This is a factor for liquid tightness and rib medial solidity at the stitched region. There is not only this straight line region 26 from one trapezoid section folded pair to the other, but abutting region 27 between the trapezoid pairs in practice eliminates gap or overlap.

What is claimed and it is desired to secure by Letters Patent is:

1. In a paper container, angularly disposed wall portions having their adjacent edges connected

5 by an intermediate elongated portion scored to a depth sufficient to provide a rib opposite the score and within the container, the inner surface of said rib providing a fillet in the corner defined by said wall portions, and a coating of paraffin or like substance adhering to the inner faces of said wall portions and rib or fillet.

2. The method of forming a leak-proof paper container which comprises, scoring a paper blank to form a groove in one surface and a rib opposite said groove thus defining adjacent container panels or wall portions mutually connected by means of a scored portion, moving said wall panels into angular relationship about said intermediate scored portion as a hinge or axis, the panels being so moved as to tend to compress the rib and to thereby form a fillet in the corner defined by said panels and within the container, securing said panels in fixed relationship, and thereafter coating the surface of the fillet and adjacent surfaces of the panels with a leak-proofing substance such as paraffin.
